PNEUMATIC CUSHION

Robert W. Sampson, Wilmington, Del., assignor
to Sampson Rubber Products Corporation of
Delaware, a corporation of Delaware

Application September 25, 1947, Serial No. 776,042

7 Claims. (Cl. 155—179)

1

This invention relates to pneumatic cushions such as are employed in connection with the manufacture of seats, mattresses and the like, and more particularly the invention is concerned with improvements in cushions of the kind characterized by projecting, hollow, spaced-apart ribs which provide elongated, weight-carrying air chambers, such a cushion being disclosed and claimed in my Patent No. 1,928,675 of October 3, 1933 and in Patent No. 2,367,628 of January 16, 1945 to M. C. Teague.

Cushions of the character referred to, as heretofore proposed, have the objection that the ribs which provide the weight-carrying air chambers, being of substantially the same depth, and of necessity relatively closely spaced, bulge laterally in response to weight to which they are subjected in such a manner that when such weight is substantial the side walls of the ribs engage one another and in so doing impair and render substantially ineffective the desired action which can only be attained when the various ribs are permitted to function independently and without interference from one another.

The principal object of the present invention, therefore, is to overcome the above objection, this object contemplating the formation and arrangement of the ribs which provide the air chambers in such a manner that lateral distortion, or bulging, of the ribs when subjected to weight is freely permitted without the ribs engaging one another and this object being attained without the necessity of increasing the spacing between the ribs in such a manner as to result in improper support of the top surface of the cushion.

A further object is to provide a cushion which will yield locally to the weight to which it is subjected but with respect to all other areas will maintain its normal shape, presenting clear-cut outlined edges and surfaces.

A still further object is to provide a cushion which is so ventilated that ready flow of air through and around the cushion is permitted.

The invention is illustrated in the accompanying drawings wherein:

Figure 1 is a top plan view of a pneumatic cushion embodying the features of the invention;

Figure 2 is a section taken along line 2—2 of Figure 1;

Figure 3 is a transverse section taken along line 3—3 of the same figure;

Figure 4 is a fragmentary section taken along line 4—4 of Figure 1;

2

Figure 5 is a top plan view of a modified form of pneumatic cushion;

Figure 6 is a section taken along line 6—6 of Figure 5;

Figure 7 is a transverse section taken along line 7—7 of Figure 5, and

Figure 8 is a fragmentary section illustrating the manner in which lateral deflection of the side walls of the lower ribs may take place without contact between adjacent ribs.

The cushion, as illustrated, is formed on its under side with a plurality of elongated ribs 10 which provide air channels and on its upper side with a plurality of transversely extending ribs 11 which also provide air channels. The upper and lower channels communicate with one another, thereby insuring that the pressure within the cushion will be uniform throughout, a suitable valve 12 being provided so that air may be introduced into the cushion, or withdrawn, as desired. As noted in my Patent 1,928,675 of October 3, 1933, such a rib arrangement has the advantage that the upper side of the cushion will yield more readily from front to rear (assuming that the cushion is employed in such a manner that the lower ribs extend from front to rear and the upper ribs extend from side to side), while the under side will yield more readily from side to side, the result being that stretching of one side of the cushion in one direction is opposed by the greater resistance to stretching offered by the other side.

In the use of the cushion, it may be covered and mounted upon a suitable frame as described in my prior patent, the terminal portions of the ribs 10, that is, the alternate ribs of greatest depth, in such case seating upon the supporting members of the frame.

Referring to Figure 2, it will be noted that alternate of the ribs 10 are of substantially greater depth than the intermediate ribs, the ribs of greater depth only being intended to contact the supporting structure. The intermediate ribs referred to provide reinforcement in the same direction as the adjacent ribs of greater depth, although not to the same degree as the latter, and afford substantial support to the top surface of the cushion between the main weight carrying ribs, preventing upward bulging of the areas where the upper ribs and the lower ribs do not contact one another.

Preferably the bottom surfaces of the weight carrying ribs are arched, as shown, in order to resist deflection of the cushion centrally and also to prevent the under side of the cushion from

sagging too much in the event that the weight to which the cushion is subjected is excessive, the terminal portions of the ribs at the opposite sides of the arched portions being adapted to provide bearing surfaces for engagement with the supporting members of the frame which is employed, if a frame is employed. It is also preferred that the web connections 13 at the points where the bottoms of the recesses between the upper ribs intersect the tops of the recesses between the lower ribs be perforated as indicated at 14 so that air may readily pass from the under side of the cushion to the upper side and vice versa.

The manner in which the cushion responds to weight to which it is subjected is illustrated in Figure 8 wherein the supporting structure for the cushion is sufficiently indicated for the purpose in view by a showing of frame member 15, the covering for the cushion forming no part of the invention and hence being omitted for purposes of clarity.

Any weight to which the cushion is subjected is transmitted through the main load carrying ribs to the frame of the supporting structure. In response to such weight, the area to which the weight is applied is compressed, the walls of the main weight-carrying ribs bulging laterally as indicated in dotted lines. During compression of the cushion in the manner described the ribs intermediate the main weight supporting ribs move downwardly. The depth of the intermediate ribs however is determined with relation to the main ribs so that bulging of the latter and downward movement of the intermediate ribs may occur without contact of the side walls of any of the main weight carrying ribs with the side walls of adjacent weight carrying ribs. The construction described therefore has the advantage that the ribs on the underside of the cushion may be spaced close enough together to support the upper surface in the desired manner without the possibility of the side walls of the ribs contacting one another when the cushion is compressed, it being understood that any such contact between the walls of adjacent ribs would materially impair the action of such ribs as it would prevent their independent operation and would in effect result in those areas in the cushion carrying such ribs responding as a single air chamber.

A modified form of cushion is shown in Figures 5, 6 and 7 wherein it will be noted that the outermost of the lower ribs 10a are of uniform depth throughout their extent while those of the intermediate main weight-carrying ribs are arched as and for the purpose heretofore described. It will be noted also that in this embodiment the ends of the lower ribs are connected by loops 16 which form in effect ribs which extend transversely with respect to the main ribs and place the ends of the latter in communication with one another. The ribs which are formed by the loops 16, being at the front and back of the cushion, also serve as added support for localized pressure such as the leg of a person sitting on the seat, it being appreciated that under such conditions the front edge of the cushion may be subjected to considerable weight and that there would be no arching effect of the cushion to support such localized pressure between the arched ribs 10. In other respects the embodiment shown in Figures 5, 6 and 7 is substantially the same as the embodiment shown in Figure 1.

From the foregoing, it will be apparent that the cushion described has the advantage that the upper surface thereof is supported firmly.

throughout its extent and that any local area subjected to weight may be compressed without objectionable distortion of adjacent or remote areas. A further advantage obtained, as noted, is that any contact between the side walls of the ribs on the under side of the cushion is prevented, although substantial distortion of the side walls of the main weight-carrying ribs is permitted. Hence the cushions when covered or upholstered will, except for the local area affected, maintain the desired predetermined shape, presenting clear-cut outlined edges and surfaces.

The two embodiments of the invention illustrated are intended as by way of example only as it will be apparent that the features of the invention may be employed to advantage in connection with pneumatic cushions wherein the shape of the latter and the shape and arrangement of the ribs may be varied considerably in accordance with the specific purpose for which the cushion may be designed.

I claim as my invention:

1. A pneumatic cushion comprising a plurality of hollow, elongated ribs which are located on the same side of the cushion and which provide air channels, alternate of said ribs being of greater depth than intermediate ribs, the ribs of greater depth providing load-carrying members and having contact areas for engagement with supporting structure and the ribs of less depth being supported above said supporting structure and serving to reinforce the opposite side of the cushion in those areas between the load-carrying members.
  2. A pneumatic cushion comprising a plurality of hollow, elongated ribs which are located on the same side of said cushion and which provide air channels, alternate of said ribs having bearing surfaces at their ends and being of greater depth than intermediate ribs.
  3. A pneumatic cushion comprising a plurality of relatively closely-spaced, hollow, elongated ribs which are located on the same side of said cushion and which provide air channels alternate of said ribs providing load-carrying members and having contact areas for engagement with the supporting structure for the cushion and the intermediate ribs reinforcing the opposite side of the cushion in the areas between the load-carrying members, said alternate ribs being of greater depth than said intermediate ribs, whereby substantial lateral deflection of the side walls of said alternate ribs may take place as a result of weight upon the cushion without engagement of said walls with said intermediate ribs.
  4. A pneumatic cushion having on one side a plurality of hollow, elongated ribs which are located on the same side of said cushion and which provide air channels, alternate of said ribs being arched and at the opposite sides of said arched portions being of greater depth than intermediate ribs to provide contact areas for engagement with supporting structure, the arched ribs providing load-carrying members and the intermediate ribs serving to reinforce the opposite side of the cushion in those areas between the load-carrying members, and transversely extending ribs on the opposite side of said cushion which also provide air channels.
  5. A pneumatic cushion having on one side a plurality of hollow, elongated ribs which provide air channels, alternate of said ribs being arched and at the opposite sides of said arched portion being of greater depth than intermediate

of said ribs, and transversely extending ribs on the opposite side of said cushion.

6. A pneumatic cushion having on one side a plurality of hollow, elongated ribs which provide air channels, alternate of said ribs being arched and at opposite sides of said arched portions being of greater depth than intermediate of said ribs, and transversely extending ribs on the opposite side of said cushion which also provide air channels, the ribs on the opposite side of said cushion being separated by common connecting web portions, said web portions being formed with breather openings.

7. A pneumatic cushion comprising a plurality of hollow, elongated ribs which are located on the underside of said cushion and which provide air channels, alternate of said ribs providing load-carrying members having contact areas for engagement with the supporting structure for the cushion and the intermediate ribs reinforcing the upper side of the cushion in the areas between the load-carrying members, said alternate ribs being arched between said contact areas

and being of greater depth at said contact areas than said intermediate ribs, whereby substantial lateral deflection of the side walls of said alternate ribs may occur as a result of weight upon the cushion without engagement of said side walls with said intermediate ribs.
